MACARONI

Donato Maldari, Brooklyn, N. Y.

Application June 8, 1951, Serial No. 15,463

Term of patent 3½ years

(Cl. D8—1)

To all whom it may concern:

Be it known that I, Donato Maldari, a citizen of the United States, residing at Brooklyn, in the county of Kings and State of New York, have invented a new, original, and ornamental Design for Macaroni, of which the following is a specification, reference being had to the accompanying drawing, forming part thereof.

Fig. 1 is a side elevation of a piece of macaroni embodying my new design;

Fig. 2 is a top plan view of the same;

Fig. 3 is a cross sectional view on substantially the plane of line 3—3 of Fig. 1.

I claim:

The ornamental design for macaroni, substantially as shown.

DONATO MALDARI.
